(57) CLAIM

The ornamental design for a pair of bags, as shown and described.

DESCRIPTION

FIG. 1 is an in use view of my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown on claimed surfaces depict claimed stitching. The broken line showing of a human figure and straps in FIG. 1 depicts environment and forms no part of the claimed design.

1 Claim, 7 Drawing Sheets

FIG. 1

FIG. 4
